UNITED STATES PATENT OFFICE

FRED LESLIE KNOWLES, OF FORT DODGE, IOWA

SUNSHINE CRIB

Application filed March 10, 1928. Serial No. 260,711.

It is the purpose of my invention to provide a sunshine crib for small children, which can be conveniently mounted in the window opening of a house in such manner as to project 5 outside the house, which crib is provided with suitable transparent parts, so that a child in the crib may receive a sunbath, while the crib may be kept warm by the circulation of air from the interior of the house.

10 Another purpose is to provide such a crib having suitable glass substitutes, which do not retard the passage of certain biologically valuable light rays, the passage of which is impeded by ordinary glass.

15 With these and other objects in view, my invention consists in the construction, arrangement and combination of the various parts of my sunshine crib, whereby the objects contemplated are attained, as herein-after more fully set forth, pointed out in my claims, and illustrated in the accompanying drawings, in which:

20 Figure 1 is a perspective view of a crib embodying my invention.

25 Figure 2 is a perspective view of one of the sliding channels containing glass substitute.

Figure 3 is a front elevation of my improved crib.

30 Figure 4 is a longitudinal, detail, sectional view of the crib, parts of the wall of the house and the window sash being shown in section; and

35 Figure 5 is a transverse, sectional view of the crib taken on the line 5—5 of Figure 1.

It may be said that generally speaking my crib includes a front wall, a top and bottom, a rear wall and side walls.

40 The front wall projects laterally and vertically beyond and above the side and top walls, so as to overlap a window frame inside a room.

The crib is really a box. It has a bottom wall, indicated generally by the reference numeral 10, preferably having spaced members 10^a and 10^b, with a dead air space 11 between them.

45 The lower half of the crib has the rear end wall 12 of construction similar to that of the

bottom, and the side walls 14 also of similar construction.

At the front of the crib is a front wall 16, which projects laterally beyond the side walls 14, as shown in Figure 1, and vertically above 55 the top of the wall of the crib, which will be hereinafter described.

At the top of the crib is a frame member A, having the side members 18 extending rearwardly from the forward wall 16, and a rear 60 member 20 connecting the members 18.

At the rear corners of the frame A are frame members 22, extending downwardly and supported on the side and rear wall members 14 and 12.

65 The rear wall 12 has the inner wall 12^a at its lower part and the rear, outer wall member 12^b, which extends upwardly to the top of the crib and supports the rear part 20 of the frame A. The upper part of the rear wall 70 12^b, as indicated at 12^c, is preferably made of glass substitute material, such as is herein-after again referred to.

75 At the sides of the crib above the side walls 14 are suitable screens 24.

Mounted in the frame A and supported thereby and by the upper part of the front wall member 16 is a pane of glass substitute 26 of the kind in which screen wire or the like is covered by a cellulose acetate solution, as for instance disclosed in the Colle et al. Patent No. 1,580,287, issued April 13, 1926.

80 In the wall 16 at proper points are openings 28 to receive panels 30, which may be slid into the crib just outside the screens 24. The panels 30 contain panes 32 of some glass substitute, such as that mentioned. The panels 30 slide between suitable guides 34.

85 When the panels 30 are in position, no drafts from the outside can enter the crib. In some weather, one or both of the panels 30 can be taken out or only partially inserted.

90 The front of the crib has a gate or door 36 hinged as at 38.

95 The door 36 and the wall 16 are provided with coacting latch members 40 and 42.

The door 36 has a latticed portion or the like 44 to allow free circulation of air between the crib and the interior of the room. 100

In Figure 4, I have shown at 46 a wall having a window opening 48, in which is a ⁵ ¹⁰ ¹⁵ ²⁰ ²⁵ ³⁰ ³⁵ ⁴⁰ ⁴⁵ ⁵⁰ ⁵⁵ ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ ¹⁴⁰ ¹⁴⁵ ¹⁵⁰ ¹⁵⁵ ¹⁶⁰ ¹⁶⁵ ¹⁷⁰ ¹⁷⁵
